UNITED STATES PATENT OFFICE.

EDWARD C. HINCKLEY, OF DELMAR, IOWA, ASSIGNOR OF ONE-HALF TO
LE ROY WEBSTER PARKER, OF SAME PLACE.

GRAIN-ELEVATOR.

SPECIFICATION forming part of Letters Patent No. 252,376, dated January 17, 1882.

Application filed October 24, 1881. (No model.)

To all whom it may concern:

Be it known that I, EDWARD C. HINCKLEY, of Delmar, in the county of Clinton and State of Iowa, have invented certain Improvements 5 in Grain-Elevators, of which the following is a specification.

This invention relates to grain-elevators, and is designed to effect the ready movement of the elevator-spout to position over the chute 10 of any desired bin and the simultaneous discharge of two or more elevators placed one behind or beside another into two or more sets of bins the chutes or hoppers of which are arranged concentrically about the respective elevators in substantially parallel rows.

The invention consists in arranging two or more elevators in line, one close beside or behind another, and providing each with a spout longer than the one before it, whereby each

15 spout is permitted to reach the hoppers or chutes to which it delivers without interference or obstruction by others; arranging a curved or semicircular track or support concentric with each elevator, which track may or may 20 not support the respective spouts, and is notched or perforated at proper intervals to receive locking devices, by which the spouts are held in position; in a novel arrangement of ropes or bands and other devices for moving 25 the spouts to the different hoppers; in the construction of indicators to show the position of the spouts, and in other details hereinafter explained.

In the accompanying drawings, Figure 1 represents 30 a perspective view of my apparatus complete, the building being broken away to show the interior; Fig. 2, a plan view; Figs. 3 and 4, views illustrating certain details.

The invention may be best understood by 35 referring to the drawings, in which A and B represent two elevator-shafts arranged one directly behind or in line with the other, and provided respectively with jointed or swinging spouts C D, the former arranged to deliver 40 into a series of hoppers or chutes, E, and the latter into a series, F. The spouts of each series are arranged concentrically about the elevator by which they are supplied, or about the center of motion of the swinging spout 45 50 through which the grain is delivered. The

spouts C and D at their outer ends each swing over or under a curved track or rail, G, notched at intervals to correspond with the different bins to which they deliver, and are provided with latches H and I or fastenings to engage 55 with said notches and hold the spout over the desired bin, as indicated in Fig. 1.

The latch may be simply a flat bar, H, pivoted at one end, moving in a guide at the opposite end, and having its operating-cord J 60 passed upward over an arm or pulley, a, thence over a like support on or near the elevator-shaft to the point at which the operator stands, as in Fig. 3; or it may consist of a bar, I, pivoted and guided like the first, but connected 65 by a link, b, with a lever, l', pivoted midway between its ends and extending inward to the side of the elevator-shaft and furnished with an operating-cord, K, as in Fig. 4.

It is apparent that other forms of fastening 70 devices may be employed—as, for instance, a spring catch or bolt—and that they may engage with the upper or lower edge or face of the track.

Under either of the above arrangements it 75 will be seen the respective spouts may be locked in position over any desired bin or hopper or chute, the latches falling of their own weight into the notches of the supporting-track G when their operating-cords are released and the spouts are brought to their proper positions. By simply pulling the latch-cords J K the latches may be disengaged from 80 the tracks G and the spouts made free to be moved to any position desired.

For the purpose of moving the spouts from one bin or hopper to another I attach to each, at or near its outer end, two ropes or bands, L M, one of which is carried to the right and passed about a pulley, c, thence inward toward 90 the side of the elevator-shaft, and around a pulley, d, and finally down by the side of said shaft to the lower floor, or other point most convenient to the operator, while the other rope or band is passed in a similar manner to the left, 95 carried about pulleys e and f, and down by the side of the elevator-shaft in the same manner, and to the same or other point, as desired.

The two ropes or bands of each spout may be attached to or connected at their outer ends 100

with a rigid section, P, so that by pulling said rigid section one rope or band will be moved in one direction, causing the other to move in the opposite direction, thereby drawing down one rope or band, and causing the spout to which it is attached to move toward that side, while the upward movement of the other band or rope permits the spout to move in such direction.

10 In some cases it may be found desirable to employ one continuous rope or band, omitting the intermediate section, or to employ a drum for each spout, around which drum the continuous band shall pass, so that by turning the drum in one or the other direction the spout shall be moved to the right or left, as desired. When drums are used they are furnished with cranks or levers by which they may be turned, and from the foregoing description it will be 15 seen that the direction in which the rigid section is pulled or the drum is rotated will govern the direction in which the spout is moved.

If the spouts be arranged to sweep through a considerable distance, they are liable to move 20 to such a position that the operating-cord will be ineffectual to start them in the reverse direction. Hence in such case I provide a third rope or band, O, attaching the same to the outer end of the spout, and carrying it under 25 a pulley or through an opening, g, in the floor, midway between the two extremes of movement, and thence down to the operator's stand. This cord will of course draw directly from the side of the spout when the latter is moved 30 to either extreme, and will consequently serve to start the spout when the main operating-ropes fail to do so. In order that there may be no mistake as to the position of the spouts by reason of the lengthening or shortening of 35 the operating ropes or bands, I prefer to employ flexible ropes or bands of sufficient length only to pass around the pulleys at the upper and lower ends of the elevator-shafts, and to interpose between said flexible portions connecting-rods of wood or metal which will not 40 appreciably lengthen or shorten. Heavy wire is well adapted for the purpose, being strong and practically free from lengthening by use, and obtainable in any desired length; but wood, 45 wire rope, iron rods, or other suitable connecting-rods may be used.

For the purpose of indicating the exact position of the spouts, one operating-band of each is furnished with a rigid section, P, held and 50 guided in staples or eyes on the side of the elevator-shaft, or on an upright post, or in other convenient position, and provided with an indicator, h, which, as the spout is moved, passes the marks or graduations of a scale, Q, 55 painted upon or secured to the side of the elevator-shaft, post, or other support, as shown in Fig. 2. The graduations may be on the rod and the indicator on the shaft.

The rigid section P may be the operating 60 section, or a special or independent section.

The graduations are lettered or numbered to indicate the respective bins, and it is there-

fore simply necessary in practice for the operator to draw the latch-cord and pull the rigid section, or turn the winding-drum N until the 70 indicator shows the spout to be nearly in the desired position, when the latch-cord is released and the movement of the rigid section or the rotation of the drum is continued until the spout reaches the proper place, whereupon 75 the latch drops into the notched track and holds the spout in position.

If desired, the spouts may be each furnished with a roller arranged to travel on a flanged supporting-track to furnish the necessary support to the spout and render its movement 80 easy.

The latches or fastenings may be reversed and arranged to engage with a rack above the 85 spouts, if preferred.

I am aware that grain-elevators have hitherto been provided with a movable spout to deliver into different bins, and that it has been proposed in one instance to effect and control the movement of the spouts by ropes passing 90 about pulleys and down to the operator's stand; but I am not aware that any one has ever arranged two or more spouts of separate elevators in such manner that they might simultaneously deliver to two or more concentric rows 95 of hoppers, that latches have been applied directly to the spout, or that the operating devices herein shown and described have ever been proposed hitherto.

By my arrangement a very large amount of 100 work can be accomplished in a very small space and short time, as compared with previously-existing plans, the spouts are held firmly and exactly in place, and the movement of the spouts is rendered quick, easy, and certain.

The drum or drums may be dispensed with, and ordinarily it is preferred to omit them, and to employ only the rigid section for operating 110 the cords or bands.

Having thus described my invention, what I claim is—

1. In combination with an elevator having a movable spout arranged to deliver into a series of concentric hoppers or bins, one or more 115 additional elevators located beside the first, and provided with spouts extending beyond the end of the spout of the first elevator to other series of hoppers or bins, whereby each spout is permitted to deliver into any one of 120 its series of hoppers without interfering with the delivery of the other.

2. In combination with a movable grain-delivery spout, operating ropes or bands attached to the same, extending outward from opposite 125 sides thereof and around pulleys or guides, and a rigid section or drum connected with the ends of said bands, and arranged to simultaneously pay out one cord and take up the other, substantially as explained.

3. In combination with a movable spout and operating ropes or bands extending from opposite sides of the same, a starting-cord attached to the spout and passing through a

guide at a point between the extremes of movement of said spout, as and for the purpose explained.

4. In combination with a movable spout, a latch or bolt applied directly thereto and arranged to engage with a fixed catch, whereby the spout is held firmly and accurately in position.

5. In combination with a movable delivery-spout and operating cords or bands arranged substantially as described, a rigid section provided with an indicator and arranged to move with the operating cord or band past the graduations of a fixed scale, substantially as shown.

10 6. In combination with the notched track G, the movable spout traveling over or under the same and provided with a latch to engage with the said track.

7. The herein-described apparatus for elevating grain and delivering it to different 20 spouts, consisting of an elevator provided with a movable spout, a track provided with a series of notches or openings, a latch or bolt attached to the spout and arranged to engage in said openings, operating-bands attached to 25 the spout and connected with a rigid section or a winding-drum, in the manner explained, a scale, and an indicator to show the position of the spout.

EDWARD C. HINCKLEY.
